LOCK

Rollo Marple, Jackson, Mich., assignor to Hancock Manufacturing Company, Jackson, Mich., a corporation of Michigan

Application August 19, 1937, Serial No. 159,940

19 Claims. (Cl. 292—165)

The present invention relates to door latches, or the like, and in particular provides an improved construction of door latch of the slideable bolt type, embodying improved features of design, and having improved operating characteristics.

Objects of the present invention are to provide a door latch, particularly suited for use on automobile doors, characterized as being simple in construction, economical of manufacture, and relatively efficient in operation; to provide such a door lock embodying a retractable bolt, a spring or the like for biasing the bolt to a predetermined position, and anti-friction means interposed between the bolt and the biasing means; to provide such a lock in which the anti-friction means takes the form of a roller interposed between the bolt and the spring, adapted to contain a supply of lubricant for the engaging surfaces; to provide such a lock embodying improved cushioning means for limiting the movement of the bolt in a projecting direction; to provide such a lock in which the cushioning means includes a relatively soft bumper of rubber or the like which becomes initially effective to retard the projecting movement of the bolt, and a stiffer bumper of rubber or the like, which becomes effective as a final stop to the projecting movement; to provide such a lock in which the bumper means is formed as a part of the retracting means for the bolt; and to provide such a lock in which the bolt, acting through the bumper means, continuously urges the retracting means and consequently the vehicle door handle towards the normal or bolt projected position thereof.

Further objects of the present invention are to provide an improved door lock embodying a first roll back member, rotatably responsive to a door handle or the like, a retractable bolt, and a second pivoted roll back member interposed between the bolt and the first roll back member for retracting the bolt in response to rotation of the first roll back member; to provide such a construction in which the second roll back member carries a resilient bumper to form a stop to the projecting movement of the bolt, against which the bolt bears to continuously urge the roll backs to their normal or bolt projected position; and to provide such a construction in which one of the roll back members includes a locking device operable by the associated inside retracting means for the bolt to lock the roll back members against actuation.

With the above as well as other objects in view, which appear in the following description and in

the appended claims, a preferred but illustrative embodiment of the invention is shown in the accompanying drawing, throughout the several views of which corresponding reference characters are used to designate corresponding parts and in which:

Figure 1 is a view in elevation of a lock embodying the invention;

Fig. 2 is a view in front elevation, taken along the line 2—2 of Fig. 1; 10

Fig. 3 is a view in transverse section, taken along the line 3—3 of Fig. 1;

Fig. 4 is a view in transverse section, taken along the line 4—4 of Fig. 1, and

Fig. 5 is a fragmentary view of a modification of the invention.

Referring to the drawing, the lock comprises generally a casing 10; a slidably retractable and projectable bolt 12; an inside retracting link 14; and a pair of cooperating outside roll back members 16 and 18. The bolt 12 and the outside roll back members 16 and 18 are supported upon the casing 10, as hereinafter described, and it will be appreciated that the inside operating link 14 may extend in accordance with conventional practice to the usual remotely located inside door operating handle.

The casing 10, which may be conventionally formed of a metal stamping or the like, comprises a base 20, which is generally planar, and a laterally turned flange 22 at the forward edge of the base. The flange 22 is provided with mounting holes 24, by which the casing may be secured within the associated door, and is also provided with a bolt opening 26, through which the nose of the bolt 12 projects. The opening 26 is preferably made large enough to accommodate a suitable lubricating element such as 28 against which the base of the bolt bears.

The bolt 12 comprises an enlarged nose or head 30, and a rearwardly extending portion 32, which are conventionally connected together as by rivets 34. The head 30 projects through the previously mentioned bolt opening 26 formed in the casing flange 24, and is guided between the previously mentioned lubricating member 28 and the base 20 of the casing. The rearwardly extending portion 32 of the bolt is supported on the casing 10 by a pin 36, which is received in an elongated slot 38 provided in the portion 32. 50

The connection between the bolt 12 and the inside retracting link 14 is illustrated as comprising a pin 40 carried by the link 14, which is slidably received in an elongated slot 42 provided in the rearwardly extending portion 32 of the bolt. 55

With this relation, it will be appreciated that a movement to the right of the link 14 causes a corresponding movement of bolt 12, withdrawing the head 30 thereof from operative engagement with the conventional door keeper (not shown). On the other hand, the elongated slot 42 permits the bolt 12 to be retracted independently of the position of the inside operating link 14. In order to adapt it for cooperation with the outside roll back members 16 and 18, the rearwardly projecting portion 32 of the bolt 12 is provided with a laterally turned shoulder 44, which normally abuts the hereinafter described buffer 46.

The bolt 12 is continuously urged to the illustrated fully projected position by a coil spring 50, one end 52 of which is received between a pair of spacer lugs 54 struck up from the base 20 of the casing 10, and the other end 56 of which acts against the rear end of the head 30 of the bolt 12. In accordance with the present invention, in order to reduce friction between the bolt 12 and the spring 50, as well as to subject the bolt 12 to a uniform biasing effect of the spring 50 independently of the position of the bolt, a roller 58 is interposed between the end 56 of the spring 50 and the rear face of the head 30. The rear end of the head 30 is arcuately formed as indicated at 60 to form a bearing surface for the roller 58. The parts are shown in the figures 30 with the bolt in its fully projected position, and with the roller 58 at what may be called the shallow end of the surface 60. If the bolt 12 is moved to the right, it will be appreciated that the end 56 of the spring 50 will be subjected to a corresponding rightward movement, and also that the point of engagement between the roller 58 and the end of spring 50 will move toward the extreme end of the spring. This relative movement between the roller 58 and the end 56 of the spring 50 causes the roller to rotate in a counter-clockwise direction as viewed in Fig. 1, and also causes the roller 58 to ride down into the deeper part of the arcuate surface 60. On the other hand, if the bolt 12 is released so that it may be projected to its illustrated position under the influence of spring 50, an opposite relative movement will occur between the ends of the spring 50 and the roller 58 causing the roller 58 to rotate in a clockwise direction as viewed in Fig. 1, which rotation will cause it to resume the position shown in Fig. 1.

It will be observed accordingly that all movement between the spring 50, the roller 58 and the surface 60 is of a rolling, as distinguished from a sliding, character, so that the friction between these parts is very materially lessened. The movement of the bolt 12 relative to the casing 10, as well as the corresponding movement of the roller 58, is of a sliding character, and in further accordance with the present invention, the roller 58 is provided with a bore 62 therethrough, which may be filled with a suitable lubricant to lubricate the engaging surfaces and reduce the friction of the just mentioned sliding movement.

It will be appreciated that the biasing effect of the spring 50 upon the bolt 12 depends primarily upon the distance from the center of the spring to the point of engagement between the roller 58 and the end 56 of the spring. A feature 65 of the present invention consists in so relating the curvature of the surface 60 to the curved form of the end 56 of the spring that the just mentioned distance remains substantially uniform during the projecting and retracting movement 70 of the bolt, so that the biasing effect of the

spring 50 remains substantially uniform, independently of the position of the bolt. This uniform biasing effect of the spring 50 is an important feature, in that it permits the bolt to be subjected to a substantial projecting force when 5 in the fully projected position, without at the same time requiring an excessive retracting force to move the bolt to the fully retracted position.

In the alternative embodiment of Figure 5, the connection between the biasing spring 50a and the body of the bolt 12a comprises a roller 63. Roller 63 is rotatably supported on the bolt 12a, by a pin 65, and is positioned between the bolt body and the casing portion 20a. The operation of the embodiment of Figure 5 thus corresponds 15 in all respects to the operation described above, with the exception that the roller 63 does not move bodily relative to the bolt 12a. The positioning of the center of the spring 50a relative to the bolt and the roller 63 is such, however, 20 that during projecting and retracting movements of the bolt, the effective radius of the spring, i. e., the distance between the point of engagement of the spring with the roller 63 and the center of the spring, remains substantially uniform. Accordingly, as in the case of the first described embodiment, the effective biasing force of the spring 50a remains substantially uniform for all 25 positions of the bolt.

The outside roll back member 16 is provided 30 with a boss 64 which has a rotative bearing fit within a corresponding opening 66 provided therefor in the base 20 of the casing 10, and is also provided with a squared opening 68 to receive the correspondingly squared spindle 70 of the 35 conventional outside door operating handle. The nose 72 of the roll back 16 bears against the nose 74 of the companion outside roll back member 18. The latter roll back member is positioned between the base 20 of the case 10 and the rearwardly projecting part 32 of the bolt 12, and is pivotally supported in the casing by the previously mentioned pin 36. The buffer 46 is connected to the roll back member 18, by means of a rivet or equivalent bearing element 76 and, as previously 40 stated, bears directly against the shoulder 44 formed on the bolt 12. The bolt 12 is continuously urged to the projected position by the spring 50, continuously bears against the buffer 46, and so urges the roll backs 18 and 16 to the 45 position as shown in Fig. 1, corresponding to the bolt projected position thereof. In addition, the roll back member 18 is provided with a continuously acting spring 78, one end of which is secured between a pair of spaced lugs 80, struck 50 inwardly from the base 20 of the casing 10, and the other end 82 of which bears against the rear face of the roll back member 18. The spring 78 is effective to retain the roll back members 16 and 18 in the illustrated bolt projected position, 55 even though the bolt 12 is retracted.

With the foregoing arrangement, it will be appreciated that a rotation of the roll back member 16 in the clockwise direction, as influenced by the spindle 70, causes a counter-clockwise rotation of the roll back member 18 about the pin 36 as a center. This latter movement moves the buffer 46 to the right, as viewed in Fig. 1, and so effects a retracting movement of the bolt 12. If the spindle 70 is released, the spring 50 returns the bolt 12 to its illustrated projected position. The return movement of the bolt 12 causes a corresponding return movement of the roll back members 16 and 18, and this return movement is also 60 65 70 75 80 85 90 95 98 99

caused in part by the continuously acting spring 78.

Preferably and as illustrated, the outside roll back member 16 is provided with a supplemental or wedging roll back member 83, in accordance with the invention disclosed and claimed in Patent 1,895,893, granted January 31, 1933, to Raymond G. Moore, and assigned to the same assignee as the present application. The supplemental roll back member 83 is provided with a squared opening to accommodate the spindle 70, and is received between the roll back member 16 and a supplemental casing or closure member 84, which is suitably secured to the back 20 of the casing, as by the one or more lugs 86. It will be appreciated that the squared openings in the roll-back members 16 and 82 are slightly larger than the squared spindle 70, so that normally this clearance would allow some little rotative movement of the spindle 70 to occur without causing a corresponding rotative movement of either the roll-back 16 or the roll-back 83. In order to overcome this, the roll-back member 83 is provided with a nose 88, so positioned with respect to the squared opening therein, that when the roll-back member 16 is in the position shown in Fig. 1, the nose 88 binds against the inner face of the casing flange 22. This binding relation causes the squared openings in the roll-back members 16 and 18 to be slightly angularly offset with respect to each other, so that the spindle 70 is securely wedged within these squared openings. Rotation of the spindle 70 in a counter-clockwise direction as viewed in Fig. 1 is prevented by this wedging action since the nose 88 of the roll-back member 83 bears against the flange. Similarly, rotation of the spindle in a clockwise direction as viewed in Fig. 1 is prevented by this wedging action since the roll-back member 16 is continuously urged to the position shown by the spring 78 and also by the bolt 12.

It will be noted that the buffer 46, in addition to constituting the means by which the outside roll-back members 16 and 18 are effective to move the bolt, also constitutes a positive but resilient limit stop to a projecting movement of the bolt 12. The provision of this resilient limit stop to the projecting movement of the bolt serves to overcome otherwise existing operating noises in the lock, and also lengthens the life of the lock parts by reducing the operating shocks thereon.

It may frequently happen, as where the door is slammed, and the bolt is forcibly retracted without causing a corresponding retracting movement of either the inside or outside retracting means, that the bolt, in being projected, will forcibly strike the buffer 46. To distribute the otherwise existing wear on the surface of the buffer 46, from this cause as well as others, it is preferred to make the buffer element 46 rotatable on the previously mentioned pin 16. For this purpose, the buffer element 46 is provided with a bushing or a sleeve 90, which is relatively freely rotatable upon the pin 76. Each retracting movement of the roll-back member 18 relative to the bolt, causes the buffer 46 to swing in an arc of which the pin 36 is the center. This arcuate movement causes the buffer 46 to move downwardly somewhat relative to the shoulder 44. This downward movement applies a rotative force to the buffer 46 so that each retracting movement of the member 18 is accompanied by a slight angular rotative movement of the buffer 46.

To further relieve the stresses on the buffer 46, as well as to further cushion the projecting move-

ments of the bolt 12, it is preferred to provide the supplemental buffer 92, which is illustrated as comprising a block of rubber or similar material. The right-hand end of the buffer 92 is disposed in the path of a laterally turned shoulder 94 formed on the rearwardly projecting portion 32 of the bolt 12. The left-hand end of the buffer 92 bears against a stop 96 secured to the base 20 of the casing 10. The buffer 92 is further supported on the casing 10 by a strap 98, one end of which is secured to the base 20 by a lug 100 struck inwardly from the latter, and the other end of which is secured thereto by the previously mentioned pin 36. The strap 98 also thus serves to retain the bolt 12 and roll-back member 18 against movement axially of the pin 36. The intermediate portion 102 of the member 98 is of generally channel form so that it at least partially surrounds the buffer 92.

The buffer 92 is preferably made substantially softer than the buffer 46, and is so positioned that the right-hand end thereof is engaged by the shoulder 94 substantially prior to the time that the buffer 46 is engaged by the shoulder 44. With this relation the relatively soft buffer 92 serves to retard the speed of the projecting movement of the bolt 12. Such projecting movement is finally stopped by the buffer 46.

In order to enable the outside retracting means to be rendered ineffective to cause a retracting movement of the bolt, the roll-back member 18 is provided with a rearwardly extending shoulder 104, which is disposed in the path of movement of the pin 40 associated with the inside link 14. In accordance with conventional practice, the operating lever (not shown) associated with the link 14 may be actuated to cause the latter to move to the left bringing the pin 40 over the shoulder 104. When so positioned, the pin 40 prevents a bolt retracting movement of the roll-back 18 and consequently of the roll-back 16 and the spindle 70. Preferably and as illustrated the slot 42 is of such a length that a retracting movement of the bolt 12 is effective to move the pin 40 out of the just mentioned blocking relation.

Summarizing the operation of the unit as a whole, it will be appreciated that the parts are shown in Fig. 1 with the bolt in the projected position. The bolt is held in this position by the spring 50, acting upon the bolt 12 through the anti-friction roller 58. At the same time, the shoulder 44 of the bolt 12 and the spring 78, acting through the roll-back member 18, holds the roll-back member 16 in the bolt projected position shown. The roll-back member 16 in turn, cooperating with the supplemental roll-back member 83, effectively holds the door spindle 70 in a predetermined rotative position, effectively preventing rattling thereof.

In order to retract the bolt 12 by the outside operating spindle 70, the latter may be rotated causing a rotation of the roll-back members 16 and 18, and causing a corresponding retracting movement of the bolt 12. Upon release of the spindle 70, the spring 50 is effective to return the bolt 12 to its projected position. Similarly, the bolt 12 and the spring 78 serve to return the roll-back members 16 and 18 to the illustrated position.

A retracting movement of the bolt 12 may also be caused by the inside link 14, independently of the position of the outside retracting means and, upon release of the inside lever, the spring 50 serves to return the bolt to its projected position. During such latter retracting movements, the

spring 78 serves to hold the outside operating means in the bolt projected position.

Further, the bolt 12 may be retracted independently of either the inside or outside retracting means, as by slamming the door, in which event, the pin 40 associated with the inside retracting means slides within the slot 42 provided therefor, and the shoulder 44 simply moves freely away from the buffer 46, without disturbing the position of the outside roll-backs 16 and 18, as influenced by the spring 78. Each projecting movement of the bolt 12 is cushioned first by the buffer 92 and finally by the buffer 46.

During each of the above described retracting movements of the bolt 12, the roller 58, which rolls relative to the bolt 12 and also relative to the spring 50, serves to eliminate any sliding contact between the parts, and so materially reduces the operating friction of the lock. At the same time, the form and arrangement of the end of the spring 50, the roller 58, and the recess 60 provided therefor in the bolt, serve to maintain the biasing effect of the spring 50 at a uniform value independently of the position of the bolt.

It will be noted that the inside link 14 may readily be positioned so that the pin 40 abuts the right-hand end of the slot 42 when the bolt is projected. With this arrangement, the initial retracting movement of the link causes a corresponding retracting movement of the bolt 12, entirely eliminating any play between the parts. In addition, due to the fact that the bolt shoulder 44 continuously bears against the buffer 46 and that the roll-back member 18 continuously bears against the roll-back member 16 and, that, finally, the roll-back member 16 is in wedged relation to the spindle 70, it will be appreciated that any play between the spindle 70 and the bolt 12 is entirely eliminated. Thus, the initial movement of the spindle 70 in a clockwise direction is effective to start the retracting movement of the bolt.

From the foregoing it will be appreciated that the present invention provides an extremely simple and effective door locking device. It will further be appreciated that various modifications in the form, number and arrangement of the parts may be made within the spirit and scope of the invention.

50. What is claimed is:

1. In a device of the class described, a movable bolt, means urging said bolt to a projected position, a retracting means adapted to be moved in one direction to retract said bolt, means limiting movement of said retracting means in the other direction so as to render said retracting means effective as a limit stop to the projecting movement of said bolt, and a relatively compressible buffer positioned for engagement by the bolt and serving to cushion final projecting movements thereof, said buffer being engageable by the bolt before the bolt reaches the limit afforded by the retracting means, and said buffer being sufficiently compressible to enable said bolt to travel to said limit afforded by said retracting means.

2. In a latch having a case plate, the combination of a movable bolt, means for urging said bolt to a projected position, a retracting means movable in one direction to retract said bolt, means limiting movement of said retracting means in the other direction so that said retracting means is effective as a limit stop to a projecting movement of said bolt, a first buffer interposed between said retracting means and said bolt, and a supplemental and relatively

softer buffer carried by the case plate and disposed in the path of projecting movement of the bolt.

3. In a device of the class described, the combination of a movable bolt, means for urging said bolt to a projected position, a retracting means movable in one direction to retract said bolt, means limiting movement of said retracting means in the other direction so that said retracting means is effective as a limit stop to a projecting movement of said bolt, and a rotatable resilient buffer interposed between said retracting means and said bolt, said engagement between the buffer and the bolt acting to rotate said buffer and distribute wear thereon.

4. In a device of the class described, the combination of a casing, a bolt slidable on said casing and having a slot therein, a spring carried by said casing and disposed to continuously urge said bolt to a projected position, a pin secured to said casing and projecting through said slot to guide the movement of said bolt, a roll-back pivoted in said casing, a pivoted member connected between said roll-back and said bolt and pivotally supported upon said pin, and an additional retracting means for said bolt having a portion movable into blocking relation to said pivoted member so as to prevent operation of said roll-back.

5. In a latch having a case plate, the combination of a bolt slidably carried by the casing for movement between retracted and projected positions, a roll-back mounted on said case plate for retracting the bolt, a retracting member interposed between said roll-back and bolt and forming an operative connection therebetween, and means common to said bolt and retracting member and forming a guide for said bolt and forming a pivotal mounting for said retracting member.

6. In a latch having a case plate, the combination of a bolt slidably carried by the casing for movement between retracted and projected positions, a roll-back mounted on said case plate for retracting the bolt, a retracting member interposed between said roll-back and bolt and forming an operative connection therebetween, means common to said bolt and retracting member and forming a guide for said bolt and forming a pivotal mounting for said retracting member, and means movable into the path of swinging movement of the retracting member for dogging said roll-back.

7. In a latch having a case plate, the combination of a bolt slidably carried by the casing for movement between retracted and projected positions, a roll-back pivotally mounted on said case plate for retracting the bolt, a retracting member interposed between said roll-back and bolt and forming an operative connection therebetween, a pin projecting from the case plate and acting to guide the bolt thereon, and a retracting member pivotally mounted on the pin and interposed between the roll-back and the bolt so as to form an operative connection therebetween.

8. In a latch having a case plate, the combination of a bolt slidably carried by the casing for movement between retracted and projected positions, a roll-back mounted on said case plate for retracting the bolt, a retracting member interposed between said roll-back and bolt and forming an operative connection therebetween, means common to said bolt and retracting member and forming a guide for said bolt and forming a pivotal mounting for said retracting mem-

ber, inside operated retracting means operatively connected to the bolt, and means actuatable by said inside operated means into blocking relation to said retracting member whereby to dog 5 said rollback.

9. In a latch having a case plate, the combination of a bolt slidably carried by the casing for movement between retracted and projected positions, a rollback pivotally mounted on said 10 case plate for retracting the bolt, a retracting member interposed between said rollback and bolt and forming an operative connection therebetween, a deck positioned in spaced relation to the case plate, a pin having its ends anchored 15 in the case plate and deck respectively, said pin

acting to guide the bolt and to provide a pivotal mounting for the retracting member, and a resilient buffer secured in place between the deck and the case plate and disposed for cushioning engagement by the bolt.

10. In a latch having a case plate, a deck secured to the case plate in spaced relation thereto, a bolt slidably mounted on the case plate and having a portion projecting between the deck and case plate, means including said deck and case plate for guiding and supporting said bolt portion, and a resilient buffer secured between the deck and case plate and disposed for cushioning engagement by the bolt.

ROLLO MARPLE. 15
